INTERNAL COMBUSTION ENGINE

Glenn L. Riley, New Orleans, La.

Application March 20, 1939, Serial No. 263,069

13 Claims. (Cl. 123—133)

This invention relates to internal combustion engines, and the present application is a continuation-in-part of my application for patent Ser. No. 140,728, filed May 4, 1937.

The object of the invention is to provide a process and apparatus for the generation of fuel vapor from heavy, that is to say, the less volatile liquid fuels, under optimum conditions of temperature and air exclusion, the mixing of the fuel vapor with air into a correct combustible mixture, and the control of the rate of generation according to the engine demands.

Other objects of the invention will appear as the following description of a preferred and practical embodiment thereof proceeds.

In the drawing the sole figure is a side sectional view showing apparatus embodying the process of the present invention, and through which the process of the invention may be carried out.

Referring now in detail to the drawing, the numeral 1 represents in general a carburetor which is here shown as being of the down-draft type, having an axially located nozzle 2 and an air inlet 3, the air entering the annular space about the nozzle 2 through spaces between the spider arms 4. The carburetor includes an adjustable metering pin 5 having a tapered end which extends within a tubular extension 6 of the nozzle. The nozzle, together with its tubular extension, is supported by pivoted vanes 7, which move responsively to the air draft created by the piston displacement of the engine. When the draft is heavy the vanes draw the tubular extension 6 downwardly with respect to the tapered end of the metering pin, increasing the fuel opening. When the draft is light, the vanes, together with the tubular extension 6, move upwardly under the urge of the spring 8, closing, more or less, the annular fuel passage between the end of the extension 6 and the tapered end of the metering pin.

The combustible mixture formed in the carburetor passes through the intake manifold 9 to the engine 10. The throttle valve 11 controls the supply of mixture admitted to the engine. The carburetor is provided with a fuel inlet passage 12 in communication with the tubular extension and nozzle.

All that has above been described is conventional. However, where such carburetors have been used, fuel in liquid form has been admitted through the passage 12 and has been atomized at the nozzle 2. The mixture has consequently been a mixture of air and very finely divided par-

ticles of liquid fuel which are supposed to completely evaporate in the air in the mixing chamber adjacent the end of the nozzle or in the intake manifold on the way to the engine. Such a mode of operation is, of course, quite feasible and well-known where volatile fuel such as gasoline is employed, but it is quite obvious that one could not expect atomized particles of heavier and less volatile liquid fuels to thoroughly evaporate in the air in the manifold.

The present invention supplants the liquid fuel supplied to the carburetor by fuel vapor generated from the heavier fuels such as kerosene, distillate or even crude oil, through the instrumentality of heat generated preferably by the engine. Heat is supplied by the exhaust from the engine, and the structural embodiment by which the invention is herein illustrated provides an exhaust pipe 13 from the engine surrounding that portion of the intake manifold which is adjacent the engine. It is not essential, however, in carrying out the broader aspects of the invention, that the exhaust pipe shall be associated with the intake manifold.

The generating system of the present invention is in the form of a circuit. It consists of a closed receptacle or chamber 14, to which liquid fuel is supplied and preferably maintained at a given level by means such as a float controlled valve 15. From the bottom of the chamber 14 a pipe 16 passes to a heating coil 17. From the heating coil a pipe 18 communicates with a down-pipe or by-pass 19, the lower end of which is open, and dips beneath the level of liquid fuel in the chamber 14. This is the circuit. The coil 17 is located within the exhaust pipe 13. For convenience, it is shown wrapped about the intake manifold but it utilizes the intake manifold solely as a means of support.

Liquid fuel from the chamber 14, entering the coil 17 is changed to a vapor, due to the heat of the exhaust, and the vapor passes through the vapor fuel pipe 18 and the down-pipe or by-pass 19 back to the body of liquid fuel in the chamber 14, where it is both condensed and absorbed. The fuel passage 12 of the carburetor taps into the fuel vapor pipe at its point of juncture with the down-pipe or by-pass, and while the engine is running there is a demand for the generated fuel vapor so that only a relatively small portion of the fuel vapor returns by way of the by-pass to the liquid fuel chamber.

Referring to the drawing, it will be noted that there is a check valve 20 in the liquid fuel pipe 16 between the fuel chamber 14 and the coil 17.

17, which prevents back flow from the coil into the liquid fuel chamber. Said check valve is maintained closed by a spring 21 strong enough to hold the body of liquid fuel in the chamber 5 14 when the engine is not running, at which time conditions are static in the generating circuit. There is a valve 21' in the liquid fuel pipe between the chamber 14 and the coil 17 which is manually adjusted at the time the engine demands are heaviest, to permit enough liquid fuel to be discharged into the coil to provide a rate of vapor generation supply in excess of the demands of the engine at that time. There is another valve 22 in the vapor fuel pipe 18 at an 10 intermediate point in said vapor fuel pipe, which may be manually adjusted in order to provide a slight excess of pressure on the coil side of said valve, above that on the carburetor side. This provides a storage of some excess fuel vapor under pressure in the system, to meet the demands of sudden throttle opening after a period of comparative idling, during which the heat of the exhaust manifold may have been reduced to a point low enough to slow up the rate of vapor 15 generation.

The construction and the arrangement of the parts constituting the generating circuit are such as to determine the generation of fuel vapor at a rate which follows very closely the 20 demands of the engine, being only slightly in excess of the engine demand. It will be understood that there is at all times, while fuel vapor is being generated, a plus pressure in all parts of the circuit and including the fuel passage 12. 25 At the time of greatest engine demand, that is to say when the pistons of the engine are creating little vacuum, the plus pressure in the liquid fuel pipe 16 above the valve 21' is at its maximum excess over the plus pressure in the 30 fuel by-pass 12, and that part of the circuit which is on the coil side of the valve 21 so that the maximum amount of liquid fuel is drawn past the check valve 20 and the valve 21'. This causes the maximum amount of vapor to be 35 generated in the coil 17. When the engine demand decreases, the plus pressure in the fuel passage 12 and the vapor limb of the circuit builds up so that the pressure differential on opposite sides of the valve 21' diminishes, and 40 less liquid fuel is drawn into the coil 17; thus, less fuel vapor is generated. In this manner, the generation of vapor follows closely the demands of the engine, it being understood that to assure an adequate supply of fuel vapor at all 45 times, the valve 21' is adjusted to permit slightly more vapor to be generated than is to be utilized, the excess being returned to the chamber 14 through the down-pipe or by-pass 19 where it is condensed or reabsorbed into the body of liquid fuel in said chamber. Further close control 50 of the proportion of fuel vapor admitted to the engine is accomplished through the relationship of the tension of the spring 8 to the weight of the liquid column in the lower end of the by-pass 19. The spring tension is slightly greater than the weight of the liquid column, so that at 55 low speeds of the engine, when the vanes 7 are not depressed, the excess vapor pressure in the circuit will force down the column of liquid in the by-pass, admitting the excess vapor to the chamber 14, rather than force down the nozzle extension 6 against the tension of the spring 8.

In its practical embodiment, the coil may be termed a flash-type vaporizer instantaneously 60 converting the liquid fuel into vapor. With this

end in view, a venturi 23 is inserted at the anterior end of the coil 17 to increase the velocity of the incoming jet of liquid fuel to throw it as far forward as possible through the convolutions of the coil. The coil is of such length 5 as to superheat the vapor which preferably has a temperature below the cracking point of the oil vapor, but well above its condensation point. Within this high temperature range the fuel vapor would be subject to spontaneous combustion 10 in the presence of oxygen, consequently, it is an important feature of the invention that the fuel vapor in its passage through the generating circuit is altogether excluded from air.

In order to prevent the fuel vapor at this high 15 temperature from bursting into a sooty smoke upon contact with air at the mouth of the nozzle of the carburetor, it is subjected to atmospheric cooling in the fuel vapor pipe 18, and also in the carburetor fuel passage 12, which is 20 in the path of the incoming air. While this cooling lowers the temperature of the fuel vapor to the point below that of spontaneous combustion, it still remains above the point of condensation.

The mixture of fuel vapor and air in the carburetor is preferably subjected to reheating on its way to the engine, to prevent the possibility of condensation. This reheating is accomplished through the fact that the portion of the intake 30 manifold between the carburetor and engine is jacketed by the exhaust manifold.

When cold, the engine is started with a volatile fuel, such as gasoline, which is supplied to the chamber 14 through the fitting 24 which 35 leads to a gasoline supply. A valve 25 selectively controls the supply of either gasoline or the heavy fuel. It is contemplated that the driver of an auto vehicle in which the present invention is installed, shall, when within a mile or 40 so of the end of his trip, operate the valve 25 to cut off the heavy fuel and admit the gasoline to the chamber 14. By the time he has run to the end of his journey the heavy fuel will all 45 have been depleted from the chamber 14 and been replenished with gasoline. The next morning, for example, the cold engine is started in the customary manner, the carburetor drawing liquid gasoline up the by-pass 19 and through the nozzle 2, the carburetor operating upon an 50 atomized mixture the same as it does in a convention installation. The valve 25 may be immediately shifted to cut off the gasoline and admit the heavy fuel. By the time the gasoline in the float chamber 14 has been depleted, the 55 coil 17 will be generating vapor, the pressure of which vapor will have depressed the liquid fuel column in the by-pass 19 so that the carburetor will now be operating upon a mixture of air and fuel vapor.

When starting a cold engine the time required for heating the coil to a vaporization temperature may be shortened by the employment of a wick heater 26, consisting of a gasoline chamber 27 located beneath the coil 17 and provided with 60 a wick which extends part way up on each side of the coil. Gasoline is admitted to said chamber through a tube 28 controlled by a valve 29 which is designed to be closed immediately after enough gasoline has been drawn to supply the wick chamber. A spark plug 30 in the wick chamber connected into the ignition system of the engine ignites the gasoline in the wick chamber.

The portion of the intake manifold directly 70 75

beneath the nozzle of the carburetor is formed with a well or depression 31, adapted to catch any drip from the carburetor and to convert it into vapor through heat acquired from the exhaust manifold.

While I have in the above description disclosed what I believe to be a preferred and practical embodiment of my invention, it will be understood to those skilled in the art that the details 10 of construction and the arrangement of parts as shown and described, are merely by way of example and not to be construed as limiting the invention as defined in the appended claims.

What I claim is:

1. In combination an internal combustion engine, a carburetor having an air inlet and a fuel nozzle discharging into a mixing chamber, a heavy fuel vapor generating system comprising a fuel circuit including a liquid fuel chamber, a vaporizer, a liquid fuel conduit connecting the lower part of said liquid fuel chamber with said vaporizer, a vapor fuel conduit connected to said vaporizer and having an open end dipping below the liquid level in said liquid fuel chamber, a pipe connecting said fuel vapor conduit to the nozzle of said carburetor, an adjustable valve in the liquid fuel conduit designed to be set with relation to the variable engine suction, to supply liquid fuel to the vaporizer at a rate to slightly exceed the fuel vapor demand of the engine, and an adjustable valve in said vapor fuel conduit designed to be set to maintain optimum excess vapor pressure in said conduit on the side of said valve toward said vaporizer.

2. The combination as claimed in claim 1, the elements comprising said fuel circuit being constructed to exclude air from said circuit.

3. The combination as claimed in claim 1, in which the temperature of generation is normally 40 above the point at which the fuel vapor will spontaneously burn, but below the cracking point, the elements comprising said fuel circuit being constructed to exclude air from said circuit to prevent the possibility of spontaneous combustion within said circuit, and means to cool said vapor to a point below that at which it will spontaneously burn, said means being anterior to the point at which the fuel vapor contacts air at the mixing chamber of the carburetor.

4. In combination an internal combustion engine, a carburetor having an air inlet, said carburetor being of that type having a metering pine and a fuel nozzle tube movable away from said metering pin responsive to engine suction to increase the fuel content of the combustible mixture, in which the opening movement is resisted by the pressure of a spring, a heavy fuel vapor generating system comprising a fuel circuit including a liquid fuel chamber, a vaporizer, a liquid fuel conduit connecting the lower part of said liquid fuel chamber with said vaporizer, a vapor fuel conduit connected to said vaporizer and having an open end dipping below the liquid level in said liquid fuel chamber, a pipe connecting said fuel vapor conduit to the nozzle of said carburetor, a valve between said liquid fuel chamber and said vaporizer to determine the supply of liquid fuel to said vaporizer, a valve 70 in the vapor fuel conduit intermediate said vaporizer and carburetor for maintaining a superior fuel vapor pressure in that part of said vapor fuel conduit on the side of said valve toward said vaporizer, the tension of said carburetor spring being slightly greater than the

weight of the column of liquid standing above the open end of said vapor fuel conduit within said liquid fuel chamber, whereby under low vacuum conditions the excess fuel vapor will selectively displace the liquid column in said fuel vapor pipe and flow to said liquid fuel chamber, rather than depress the fuel nozzle tube and unduly enrich the mixture in the carburetor.

5. In combination an internal combustion engine including an exhaust pipe, a carburetor 10 having an air inlet and a fuel nozzle discharging into a mixing chamber, a heavy fuel vapor generating system comprising a fuel circuit, including a liquid fuel chamber, a vaporizer, a liquid fuel conduit connecting the lower part of said liquid fuel chamber with said vaporizer, a vapor fuel conduit connected to said vaporizer and having an open end dipping below the liquid level in said fuel chamber, a pipe connecting said fuel vapor conduit to the nozzle of said carburetor, 20 an adjustable valve in the liquid fuel conduit designed to be set, with relation to the variable engine suction, to supply liquid fuel to the vaporizer at a rate to slightly exceed the fuel vapor demand of the engine, said vaporizer being 25 within said exhaust pipe and heated by the exhaust from the engine.

6. In combination an internal combustion engine, including an exhaust pipe, a carburetor having an air inlet, and a fuel nozzle discharging into a mixing chamber, a heavy fuel vapor generating system comprising a fuel circuit including a liquid fuel chamber, a vaporizer located within said exhaust pipe and heated by the exhaust from the engine, a liquid fuel conduit 30 connecting the lower part of said liquid fuel chamber with said vaporizer, a vapor fuel conduit connected to said vaporizer and having an open end dipping below the liquid level in said fuel chamber, a pipe connecting said fuel vapor 40 conduit to the nozzle of said carburetor, a spring closed check valve in said liquid fuel conduit to prevent back flow of liquid fuel into said liquid fuel chamber and to prevent flow of liquid fuel from said liquid fuel chamber to said vaporizer 45 when there is no pressure differential in said circuit, an adjustable valve in said liquid fuel conduit designed to be set with relation to the variable engine suction, to supply liquid fuel to the vaporizer at a rate to slightly exceed the 50 fuel vapor demand of the engine, the excess fuel vapor passing through the open end of said vapor fuel conduit into said liquid fuel chamber.

7. In combination an internal combustion engine including an exhaust pipe, a carburetor having an air inlet, and a fuel nozzle discharging into a mixing chamber, an intake pipe leading from said mixing chamber to said engine, a heavy fuel vapor generating system comprising a fuel circuit including a liquid fuel chamber, a vaporizer, 60 said exhaust pipe enclosing said vaporizer and jacketing said intake manifold, a liquid fuel conduit connecting the lower part of said liquid fuel chamber with said vaporizer, a vapor fuel conduit connected to said vaporizer and having an 65 open end dipping below the liquid level in said fuel chamber, a pipe connecting said fuel vapor conduit to the nozzle of said carburetor, an adjustable valve in the liquid fuel conduit designed to be set with relation to the variable engine suction, to supply liquid fuel to the vaporizer at a rate to slightly exceed the fuel vapor demand of the engine, said excess fuel vapor being returned to the liquid fuel chamber through the open end of said vapor fuel conduit, the elements comprising 70

ing said fuel circuit being constructed to exclude air from said circuit, the portion of said vapor fuel conduit adjacent said carburetor, and including the pipe which connects said fuel vapor conduit to the nozzle of said carburetor being exposed to atmospheric cooling to prevent spontaneous combustion of the fuel vapor at the mixing chamber of the carburetor, the mixture from said carburetor passing through the exhaust pipe 10 jacketed intake pipe on its way to the engine.

8. Process for preparing combustible mixture for an internal combustion engine employing the vapor of heavy hydrocarbon oils as a fuel constituent comprising, conducting the fuel in a circuit in the course of which heavy liquid fuel is vaporized at a rate proportional to engine demands and in slight excess of said demands, and the excess vapor returned to the body of liquid fuel in said circuit, carrying out the vaporization 15 at a temperature sufficiently above the condensation point of the vapor to ensure against condensation of the vapor in said circuit up to the point at which said excess vapor enters the body of liquid fuel, excluding the fuel throughout said circuit from air, conducting fuel vapor from said circuit to a carburetor, cooling the thus conducted vapor prior to its reaching the mixing chamber of the carburetor sufficiently to prevent spontaneous combustion, but not sufficiently to cause 20 condensation and mixing the thus cooled vapor with air.

9. Process for preparing combustible mixture for an internal combustion engine comprising vaporizing a relatively non-volatile hydrocarbon fuel constituent by application of heat thereto at a range of temperature below the cracking point but above the oxidizing point of the hydrocarbon, with exclusion of air, conducting the vapor toward a mixing point, successively at the 25 temperature range at which it was generated, with exclusion of air, then prior to its reaching the mixing point, cooling it to a temperature above its point of condensation but below its oxidizing temperature, the cooling being done with 30 exclusion of air, mixing the thus cooled vapor with air at the mixing point, and conducting the mixture to an internal combustion engine while maintaining its temperature above the condensation point of the hydrocarbon constituent.

10. In combination, an internal combustion engine, a carburetor having an air inlet, a conduit adapted to connect the outlet of said carburetor to the intake of an internal combustion engine, a source of liquid fuel supply of a pipe connected 55 at one end adjacent said outlet to said source of fuel supply and having a portion thereof formed as a coil around said conduit, and connected at its other end to the air intake of said carburetor, a pipe connected to the exhaust of said engine and enclosing said coil and the part of said conduit encircled thereby, said pipe being provided with a slot directly below said coil, a receptacle closing said slot, a wick in said receptacle, valve controlled means for connecting said receptacle 60 to said source of fuel supply, and means for igniting the fuel saturated wick in said receptacle to apply a priming heat to said coil and that part of the conduit encircled thereby.

11. In combination, an internal combustion engine, a carburetor having an air inlet, a conduit

adapted to connect the outlet of said carburetor to the intake of an internal combustion engine, a source of liquid fuel supply, a pipe connected at one end adjacent said outlet to said source of fuel supply and having a portion thereof formed as a coil around said conduit, and connected at its other end to the air intake of said carburetor, a pipe connected to the exhaust of said engine and enclosing said coil and the part of said conduit encircled thereby, said pipe being provided with a slot directly below said coil, and means connected to said source of fuel supply and operable through said slot to apply a priming heat to said coil and that part of the conduit encircled thereby.

12. In combination with a carburetor having an air inlet and a fuel nozzle discharging into a mixing chamber, a heavy fuel vapor generating system comprising a fuel circuit including a liquid fuel chamber, a vaporizer, a liquid fuel conduit connecting the lower part of said liquid fuel chamber with said vaporizer, a vapor fuel conduit connected to said vaporizer and having an open end dipping below the liquid level in said liquid fuel chamber, a pipe connecting said fuel vapor conduit to the nozzle of said carburetor, an adjustable valve in the liquid fuel conduit designed to be set with relation to variable air flow through said carburetor air inlet to supply liquid fuel to the vaporizer at a rate to slightly exceed the demand of said carburetor and an adjustable valve in said vapor fuel conduit designed to be set to maintain optimum excess vapor pressure in said conduit on the side of said valve toward said vaporizer.

13. In combination with a carburetor having an air inlet, said carburetor being of that type having a metering pin and a fuel nozzle tube movable away from said metering pin responsive to variable air flow through said air inlet to increase the fuel content of the combustible mixture, in which the opening movement is resisted by the pressure of a spring, a heavy fuel vapor generating system comprising a fuel circuit including a liquid fuel chamber, a vaporizer, a liquid fuel conduit connecting the lower part of said liquid fuel chamber with said vaporizer, a vapor fuel conduit connected to said vaporizer and having an open end dipping below the liquid level in said liquid fuel chamber, a pipe connecting said fuel vapor conduit to the nozzle of said carburetor, a valve between said liquid fuel chamber and said vaporizer to determine the supply of liquid fuel to said vaporizer, a valve in the vapor fuel conduit intermediate said vaporizer and carburetor for maintaining a superior fuel vapor pressure in that part of said vapor fuel conduit on the side of said valve toward said vaporizer, the tension of said carburetor spring being slightly greater than the weight of the column of liquid standing above the open end of said vapor fuel conduit within said liquid fuel chamber, whereby under low air flow conditions in the carburetor, the excess fuel vapor will selectively displace the liquid column in said fuel vapor pipe and flow to said liquid fuel chamber, rather than depress the fuel nozzle tube and unduly enrich the mixture in the carburetor.
